(74) Attorney, Agent, or Firm — Che-Yang Chen; Law
Office of Michael Chen(57) **CLAIM**The ornamental design for a shoe sole, as shown and
described.**DESCRIPTION**FIG. 1 is a perspective view of the shoe sole showing my
new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

1 Claim, 7 Drawing Sheets---
